CARPET SHAMPOOING MACHINE ATTACHMENT

Charles J. Paul, New York, N. Y.

Application August 15, 1956, Serial No. 42,611

Term of patent 14 years

(Cl. D9—2)

FIG. 1.

FIG. 2.

FIG. 3.

FIG. 4.

Fig. 2 is a side elevational view thereof,

Fig. 3 is a rear elevational view, and

Fig. 4 is a top plan view thereof.

I claim:

The ornamental design for a carpet shampooing machine attachment, substantially as shown.
